United States Patent Office.

ASA T. BROOKS, OF NEW BRITAIN, CONNECTICUT, ASSIGNOR TO RUSSELL AND ERWIN MANUFACTURING COMPANY, OF SAME PLACE.

Letters Patent No. 77,165, dated April 28, 1868.

IMPROVEMENT IN KEY-HOLE GUARD FOR DOOR-LOCKS.

The Schedule referred to in these Letters Patent and making part of the same.

TO ALL WHOM IT MAY CONCERN:

Be it known that I, ASA T. BROOKS, of New Britain, county of Hartford, and State of Connecticut, have invented certain new and useful Improvements in the Manufacture of Locks or Latches; and to enable others skilled in the art to make and use the same, I will proceed to describe the same by referring to the drawings, in which the same letters indicate like parts in each of the figures.

The nature of this invention will be understood from the specification and drawings.

In the manufacture and sale of locks or latches, it is a great desideratum to have the mechanism thereof so constructed and arranged as to effectually prevent or cut off skeleton-keys or burglars' implements from being successfully plied thereto through the key-hole. Several attempts have been made to effect this object, such as inserting a slotted thimble between the plates of the lock or latch, directly against the key-hole, and securing an arm to one side of said thimble to actuate the bolt, and also securing thereto a plate to close up a portion of the key-hole, so that, when the stem of the key is inserted into said thimble, the bit thereof, which actuates the tumblers, will slide down and protrude through the said slit formed in the thimble, and, when the key is turned, its action will cause the thimble with its arm and plate acting in unison with the bit of the key to close that portion of the key-hole unoccupied by the stem of the key, and retracts the bolt, and, when the key is withdrawn, the tumbler is left in the position to re-insert the key.

This arrangement is very liable, from accident or design, to be misplaced, or its proper action obstructed, and thereby render it difficult if not impossible to insert the key. Other and unsuccessful efforts have been made to secure this thimble in a fixed position, as when the key is withdrawn.

The object of this invention is to supersede the use of a thimble, and substitute therefor what I call an "oscillating-guard or ward-bar."

In the accompanying drawings—

Figure 1 is a face view of a lock or latch, having the cap-plate removed, showing the arrangement of its mechanism; also a face and edge view of the latch and "oscillating-guard or ward-bar;" also a face view of the tumblers detached from the case.

Figure 2 is a face view of a lock or latch, having the cap-plate removed, showing the arrangement of its mechanism in a modified form; also a face and edge view of the "oscillating-guard or ward-bar," and a face view of the tumblers detached from the case.

a is the case, broken away, in fig. 1, just above the latch, and in fig. 2 just below the "oscillating-guard or ward-bar."

a' is the face-plate of the lock or latch.

a'' is the bolt or latch of the lock.

a''' is a portion of the yoke, connected to the back end of the latch.

This case, face-plate, bolt, or latch, and the manner of attaching the yoke to the back end thereof, are effected in the usual way.

h are the tumblers, which oscillate on stud-pins *h'*, and are actuated by springs in the usual way.

A is the "oscillating-guard or ward-bar," which has its bearing and oscillates upon the fulcrum-pin *c*.

It will be seen, by the two examples shown, that this bar *A* may be made of different forms and shapes, while the same result or action is produced thereby.

B is a cut-off, which, when the bar is moved forward, closes up the key-opening, except so much as is or may be occupied by the stem of the key.

C is a ward, arranged upon said bar, which allows or prevents the proper action of the tumblers.

D is a stud, or portion of the bar *A*, which serves to throw back the latch-bolt by the action of the key and permission of the tumblers.

This bar is reacted or held back in its proper position by a double-acting spring, *E*, which coils around the

fulcrum-pin c , one end of which takes its bearing against a boss, d , or its equivalent, and the other end against the stud-pin d' formed on the bar A .

The lower end of the yoke a'' is connected to the back end of the bolt a'' , and the upper end of the bar A acts against the lower end of the yoke a''' , or its equivalent, to throw back the latch a'' .

The openings or notches f through or near the ends of the tumblers have their particular office in the operation of the mechanism, either to prevent or allow the bar A to move or oscillate to actuate the bolt a'' .

F is a hole or stem, for the support of the body of the key.

Now, it will be seen that by inserting the key of the lock or latch, and turning it forward in the usual way, the bit will strike the bar A , and cause it to move forward with its ward C , which enters the ward-openings, and allows the bolt or latch to move back into the case of the latch, at the same time the cut-off closes all of that portion of the key-hole opening through which the bit of the key enters the case; but if a strange key be inserted, even though it be very nearly like the original, and even if all the tumblers were raised, lacking one, exactly as by the original key, and that one very slightly fails to receive the ward, the action of the whole is at once arrested; and any effort to actuate the tumblers and latch by means of burglars' implements will be found still more difficult, because, in order to effect a retraction of the bolt, the tumblers must be lifted, and the bar A must be oscillated, and, in the first short movement of the bar, the whole of the bit-portion of the key-hole is closed up by the cut-off, leaving only a hole, the diameter of the body of the key, in which to ply instruments for picking the lock. Thus I am enabled to overcome obstacles and objections heretofore raised, and produce a cheap, simple, and efficient article of use and trade.

I believe I have thus shown the nature, construction, and advantage of this invention, so as to enable others skilled in the art to make and use the same therefrom.

What I claim, therefore, and desire to secure by Letters Patent, is—

The combination and arrangement of the oscillating spring-guard or ward-bar A , with the latch and tumblers, substantially as and for the purpose described.

ASA T. BROOKS. [L. S.]
